FEELER FOR LOOMS

Filed March 25, 1921

FIG. 1.

Inventor:
Edward S. Stimpson.
by his atty *Arthur S. Brown*

UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER FOR LOOMS.

Application filed March 25, 1921. Serial No. 455,533.

To all whom it may concern:

Be it known that I, EDWARD S. STIMPSON, of Hopedale, in the county of Worcester and State of Massachusetts, have invented 5 a new Feeler for Looms, of which the following is a specification.

The invention is an improvement upon the feeler mechanism set forth in United States Letters Patent No. 1,309,226, July 8, 10 1919, and consists in the feeler construction.

In accordance with the present invention, the feeler is constructed so as to contact with the weft more closely into the angle between the head and shank of the bobbin 15 than in the case of the feeler illustrated in the aforesaid patent. This is especially important in the case of bobbins for special weaves, such as mohair, upon which the initial windings of weft are wound close 20 to the angle between the head and shank of the bobbin.

The improvement is illustrated in the accompanying drawings, wherein—

Figure 1 is a plan view of the feeler 25 mechanism showing the feeler tip in contact with the weft on a full bobbin. Fig. 2 is a plan view showing the action of the feeler tip when the weft is at the critical stage of exhaustion. Fig. 3 is a cross-section 30 in the plane indicated by the line 3—3 in Fig. 1.

The drawings illustrate a bobbin such as is employed with mohair weaves, wherein the corrugated shank A is formed with alternating depressions and projections, the initial windings B of weft being wound in the depression which is close to the angle between the shank and head C of the bobbin. It is apparent from a comparison 35 between the organization shown in the aforesaid Stimpson patent and that illustrated in the accompanying drawings, that with the organization of said patent the feeler would perform its side-slipping movement long 40 before the weft in its unwinding reached the condition shown in Fig. 2 of the accompanying drawings.

In accordance with the present invention, the laterally slipping guided feeler shank 45 D is outwardly bent toward the head of the bobbin, as shown at E, at its rear, and is thence inwardly bent to form the extending toothed tip F, at the extreme rear of the feeler. This tip extends laterally 50 from the rear bend of the feeler shank and

inwardly toward the mouth of the shuttle box. By reason of this construction the teeth on the feeling surface of the tip are brought closer to the head of the bobbin than would otherwise be the case. As shown 60 in the drawings, the relation between the feeler arm and the tip is such that a rearward prolongation of the inner face G, of the feeler shank intersects the toothed portion of the tip F. With this construction, 65 the feeler teeth continue to contact with the weft until it is so far exhausted that the toothed end of the feeler comes in contact with the first projection a on the bobbin shank beyond the depression near the bobbin 70 head in which the initial bunch B of weft is wound. Fig. 2 shows in dotted lines the position of the feeler tip when its toothed face effectively encounters this initial bobbin shank projection. As the tendency of the feeler to slip sidewise is no longer resisted by the weft, the feeler tip slips laterally on the smooth surface of the bobbin shank to the position indicated by the full lines in Fig. 2, thereby setting 75 into motion the train of weft replenishing mechanism as set forth in the aforesaid patent.

Fig. 1 of the present drawings shows the parts of the feeler mechanism which immediately cooperate with the feeler arm. 80 These cooperating parts are the same as those of the aforesaid patent. It now suffices to say that the feeler shank is moved forwardly by the impact of the bobbin, and it is moved rearwardly by a spring H. The feeler shank is guided by the front swivel guide I, and the rear slotted guide J. When the feeler arm slips laterally as indicated in Fig. 2, a controller K, is moved laterally, thereby initiating the action of the weft replenishing mechanism whereby replenishment of weft occurs before the running weft is completely exhausted. The 85 feeler teeth are shown as similar to those set forth in Letters Patent of the United States, No. 1,380,940, June 7, 1921.

It will be noted from the drawing that the shank of the feeler inclines laterally and inwardly with respect to the front wall 90 of the shuttle and to the shuttle box front so that the impact of the weft tends to cause the feeler to slip laterally and inwardly away from the head of the weft carrier and toward the shuttle box mouth, 95 100 105 110

as indicated in Fig. 2. The bend E at the rear of the feeler extends laterally and outwardly from the rear of the shank toward the head of the bobbin and in a direction laterally and outwardly inclined with respect to the front wall of the shuttle, as shown in Fig. 1, and in dotted lines in Fig. 2. The toothed tip of the feeler extends laterally and inwardly from the extreme rear of the outward bend toward the shuttle box mouth, and, as the result, the feeler teeth are brought close to the initial weft windings near the head of the bobbin.

I claim—

15 An inclined side slipping feeler having its shank laterally and inwardly inclined with respect to the front wall of the shuttle and to the shuttle box front so that the impact of the weft tends to cause the feeler

to slip laterally and inwardly away from 20 the head of the weft carrier and toward the shuttle box mouth, said feeler having an outward bend at its rear where it enters the shuttle box, said bend extending laterally and outwardly from the rear of the 25 shank toward the head of the bobbin and in a direction laterally and outwardly inclined with respect to the front wall of the shuttle, and said feeler having a toothed tip extending laterally and inwardly from the 30 extreme rear of said outward bend toward the shuttle box mouth, whereby the teeth are brought close to the initial weft windings near the head of the bobbin.

In witness whereof, I have hereunto 35 signed my name.

EDWARD S. STIMPSON.
